UNITED STATES PATENT OFFICE.

ENGELBERT STROBL, OF BALTIMORE, MARYLAND.

MUSICAL TOY.

1,400,386.

Specification of Letters Patent. Patented Dec. 13, 1921.

Application filed March 17, 1921. Serial No. 452,970.

To all whom it may concern:

Be it known that ENGELBERT STROBL, a citizen of the United States of America, residing at Baltimore, State of Maryland, 5 has invented new and useful Improvements in Musical Toys, of which the following is a specification.

The object of the invention is to provide an attractive musical toy adapted to be used 10 as an ornament for Christmas trees and the like and designed to afford a representation or imitation of chimes by utilizing a current of heated air as the motive agent for actuating the movable element thereof, such current or column of air being created artificially and if preferred locally with relation to the device or being supplied by a suitable heating apparatus which may be utilized for the purpose by a suitable location of the 15 toy; and with this object in view the invention consists in a construction and combination of parts of which a preferred embodiment is shown in the accompanying drawings, wherein:—

20 Figure 1 is a side view of the device.

25 Fig. 2 is a plan view of the holder for supporting the sounding elements.

Fig. 3 is a sectional view on the plane indicated by the line 3—3 of Fig. 1.

30 The apparatus consists essentially of a holder or support 10 which may be of annular or ring form spanned by intersecting diametrical bars 11 for supporting sounding elements such as resonant plates 12, and a 35 striker 13 mounted and supported to describe a circular path in which said sounding elements are arranged, so as to successively encounter said elements and cause a succession of tones or rings which may be

40 varied in pitch to represent the intervals between the tones of bells tuned to act as chimes. The knocker or sounder is preferably loosely suspended as by means of a pendent cord 14 from a rotary carrier 15 45 consisting in the construction illustrated, of a spiral coil or turbine having a flat blade exposed to a current of air moving in the direction of the axis of the spiral, said carrier being pivotally mounted at its upper

50 end by means of a supporting pin 16 carried by a standard or upright 17 which is shoulered as at 18 to support the holder 10 which latter also serves as a means of supporting a housing 19 preferably constructed in the 55 form of a bell and inclosing the carrier, sounding elements and knocker or tongue 13,

and also preferably being perforated or constructed of wire screen or the equivalent thereof to avoid interference with an upwardly moving current of air which may be 60 supplied locally by means of candles 20 for the support of which candle sticks or holders 21 are mounted upon a base 22 in which the lower end of the standard is stepped and which standard may be hollow to form a 65 socket which may be fitted upon the upper end of a limb of a Christmas tree or like supporting object.

The apparatus may be further ornamented by the arrangement of a star 23 surmounting the bell shaped housing and figures 24 representing angels detachably mounted by means of brackets 25 on the holder 10 preferably between the planes of the candle sticks or holders. 75

The sounding or resonating elements may as indicated consist of flat plates of metal such as brass or bell metal disposed in upwardly and outwardly inclined or oblique position with their stems 26 attached to the 80 cross bars 11 of the holder.

The figures 24 may as illustrated consist of flat plates which at their lower ends are positioned as indicated between the holders for the heating units to serve as guards to 85 prevent side currents of air from affecting the flame of the candles or like objects serving as heating units and insure the upward progress of a column of heated air of a sufficient volume to effectively actuate the 90 spirally coiled ribbon constituting the carrier which supports the sounder or tongue.

Having described the invention, what is claimed as new and useful is:—

1. A musical toy having a rotary carrier, 95 a knocker or tongue loosely suspended from the carrier and a series of sounding or resonating elements arranged in the path of movement of said knocker or tongue, the carrier consisting of an axially suspended spiral 100 coil of ribbon, and said carrier and sounding elements being inclosed in a bell shaped housing of reticulated material.

2. A musical toy having a rotary carrier, a knocker or tongue loosely suspended from the carrier and a series of sounding or resonating elements arranged in the path of movement of said knocker or tongue, the carrier consisting of an axially suspended spiral coil of ribbon, and said carrier and sounding elements being inclosed in a bell 110 shaped housing of reticulated material be-

neath which is arranged a holder for a heat generating unit.

3. A musical toy having a rotary carrier, a knocker or tongue loosely suspended from the carrier and a series of sounding or resonating elements arranged in the path of movement of said knocker or tongue, the carrier consisting of an axially suspended spiral coil of ribbon, and said carrier and sounding elements being inclosed in a bell shaped housing of reticulated material beneath which is arranged a series of candle stick holders or sockets.

4. A musical toy having a rotary carrier, a knocker or tongue suspended from the carrier, a series of sounding or resonating

elements arranged in the path of the sounder or tongue, a housing of reticulated material inclosing the carrier and sounding or resonating elements, said carrier consisting of a spirally coiled ribbon suspended at its upper end, and means for producing an upwardly moving column of air through the housing and consisting of a plurality of heating units disposed beneath the plane of the bottom of the housing and guards suspended from the housing and occupying positions between the heating units for protecting the same from side currents of air.

In testimony whereof he affixes his signature.

ENGELBERT STROBL.
